United States Patent Office.

CHRISTOPHER BLAKE, OF BOSTON, MASSACHUSETTS.

Design No. 3,925, dated March 22, 1870.

DESIGN FOR AN UMBRELLA-STAND.

The Schedule referred to in these Letters Patent and making part of the same.

To all whom it may concern:

Be it known it is known that I, CHRISTOPHER BLAKE of Boston, in the county of Suffolk and State of Massachusetts, have invented a new Design for an Umbrella-Stand, of which the following is a full, clear, and exact description, reference being had to the accompanying photograph making part of this specification.

The object of my invention is to produce an ornamental and unique design for an umbrella-stand, and consists is a rack or standard composed of two portions united at their backs, so as to form a right angle, and supported upon a base whose back is also of a corresponding form, so that the stand may fit into the corner of an entry or apartment.

In the photograph, A is a standard, consisting of two portions, *a b*, united at their backs, so that the lines 1 2 and 2 3, bounding their lower edges will intersect each other at an angle of ninety degrees.

Each portion *a b* of this standard is provided near its upper end with a curved rest or rack, *c*.

Supporting this standard A is a base, B, the center of which is provided with an opening for the reception of an ornamental pan, C, of any suitable material.

The lines forming the back of the base B also intersect each other at right angles, so that the stand may snugly fit into the corner of an apartment.

Claim.

What I claim as my invention, and desire to secure by Letters Patent, is—

The design for an umbrella-stand, substantially as shown and described.

Witness my hand this 3d day of March, A. D. 1870.
Witnesses: CHRISTOPHER BLAKE.
